Primary Examiner — Jennifer L Watkins*(74) Attorney, Agent, or Firm* — Law Office of John K. Pike, PLLC(57) **CLAIM**

The ornamental design for a shoe sole, as shown and described.

DESCRIPTION

FIG. 1 is a perspective view of the shoe sole according to the present invention;

FIG. 2 is a left side view of the shoe sole of FIG. 1;

FIG. 3 is a right side view of the shoe sole of FIG. 1;

FIG. 4 is a front view of the shoe sole of FIG. 1;

FIG. 5 is a back view of the shoe sole of FIG. 1;

FIG. 6 is a top view of the shoe sole of FIG. 1; and,

FIG. 7 is a bottom view of the shoe sole of FIG. 1.

The dash dot dash broken line depicts the claim boundary and forms no part of the claim. The grayed out portion inside the claim boundary forms no part of the claim.

1 Claim, 7 Drawing Sheets(56)
